UNITED STATES PATENT OFFICE.

FREDERICK YUNCK, OF BRYAN, OHIO.

DESIGN FOR A SHELF-TABLE.

SPECIFICATION forming part of Design No. 28,365, dated March 8, 1898.

Application filed December 11, 1897. Serial No. 661,567. Term of patent 7 years.

To all whom it may concern:

Be it known that I, FREDERICK YUNCK, a citizen of the United States, residing at Bryan, in the county of Williams and State of Ohio, have invented and produced a new and original Design for Shelf-Tables, of which the following is a specification, reference being had to the accompanying drawing, forming part thereof.

The figure is a perspective view of a shelf-table, showing my new design.

As shown in said drawing, the leading or material feature of my design consists of the lower series of shelves A, having their outer or front edges formed convex, said convexity beginning at a little distance from the ends of said shelves, and their inner or rear edges formed concave, said concavities correspond-

ing in their contours with the convexed outer edges. The top shelf B has its outer or front edge also formed convex to correspond with the convexity of the other shelves, but has its inner or rear edge also formed convex to correspond with its outer edge, as shown.

Having thus described my invention, what I claim as new, and desire to secure by Letters Patent, is—

The design for a shelf-table, substantially as herein shown and described.

In testimony whereof I have hereunto affixed my signature in the presence of two subscribing witnesses.

FREDERICK YUNCK.

Witnesses:

JOHN Q. ABRAHAM,
JOHN M. CALKINS.
